UNITED STATES PATENT OFFICE

BENJAMIN SETTEL, OF NEW YORK, N. Y.

MEMORANDUM PAD

Application filed November 23, 1929. Serial No. 409,309.

This invention relates to improvements in memorandum pads of the type on which memorandums or notes may be made by the pressure of a stylus or the like passing over the writing surface and which surface may be readily cleared for placing the same in readiness to receive another written memorandum, whereby the pad may be termed a perpetual one.

10 I appreciate that various types of memorandum pads similar in principle to that above mentioned have been constructed in which a varied assortment of means have been devised for clearing or erasing the written memorandum from the pad, such as sliding bands and the like for separating the tissue sheets from the waxed or paraffin member, which requires two hands to operate, one for holding the pad stationary and the other for sliding the erasing band lengthwise of the pad. In my invention the waxed or paraffin member may be instantly moved to a position away from the tissue to clear the writing surface by the use of but one finger 25 of one hand of an operator, thus allowing free use of the other hand for supporting a telephone receiver when making memorandums over the telephone, or for any other use desired.

30 Another object of the invention is to provide a perpetual memorandum pad in which the paraffin or waxed member is normally urged against the tissue sheets by spring means, and manipulative means associated 35 with said paraffin or waxed member for effecting the depressions on the said member against the action of the spring means to clear the impression left on the tissue by the movement of a stylus thereover.

40 With these and other objects in view the invention resides in the certain novel construction, combination and arrangement of parts, the features of which are hereinafter fully described, are particularly pointed out 45 in the appended claim, and are illustrated in the accompanying drawings, in which:

Figure 1 is a perspective view of my improved memorandum pad.

Figure 2 is a vertical longitudinal sectional 50 view therethrough.

Figure 3 is a top plan view of the pad with parts broken away in section.

Figure 4 is a detail vertical sectional view on the line 4—4 of Figure 2.

Figure 5 is a vertical longitudinal sectional 55 view through a modified form of my invention.

Figure 6 is a fragmentary top plan view of the same.

Referring to the drawings by reference 60 characters, the numeral 10 designates my improved memorandum pad in its entirety and which includes a rectangular shaped casing 11 embodying an inclined top wall 12 and a removable back or bottom wall 13. The 65 top inclined wall 12 is provided with a rectangular shaped window opening 14, while mounted within the casing 11 is a frame member 15 also having a rectangular shaped opening 16 therein which registers with the window 14 in the top wall. This frame member 15 carries a transparent glossy sheet 17 which may be celluloid or the like and which serves to close the window opening 14 in the casing, while disposed beneath the transparent sheet 70 17 is a soft pliable tissue sheet 18. The frame member 15 is held in position against the inclined top wall 12 by a movable back plate 19, the upper side of which is provided with a raised portion 20 of a size to freely fit into 75 the frame opening 16 of the frame 15, the said raised portion 20 being provided with a waxed or paraffin coating 21 which is of a contrasting color than the color of the tissue sheet 18 and is preferably black.

80 The plate 19 is loosely mounted within the casing but is held in a normal position against the tissue sheet 18 by expansion springs 22 which are interposed between the plate 19 and the bottom wall 13 of the casing. 85 The springs 22 are disposed on equal sides of the longitudinal center of the plate so as to impart an even pressure to the plates. The springs as before mentioned act against the plate 19, which in turn maintains the frame member 15 in position against the inclined top wall 12 of the casing.

90 Integral with the upper end of the plate 19 and extending through a slot 23 in the upper end wall of the same is an arm or 95

handle 24, which when depressed will cause the plate 19 to move downward into the casing away from the tissue 18 for a purpose to be presently described. During the downward movement of the plate, the bottom end of the plate fulcrums against the under side of the frame 15 to prevent any downward movement of said frame, the upper end of the frame being supported in a bridge piece or bracket 25.

10 In practice, assume that the pad is clear of any writing and it is desired to record a memorandum thereon, at which time the operator grasps the stylus 26 which is captively mounted to the casing by a flexible cord 27 and proceeds to guide the pointed end of the stylus over the smooth glossy sheet 17 and in so doing, the impression of the stylus causes the soft pliable tissue 18 to 15 adhere or stick to the wax or paraffin coating 21, thus visibly displaying through the transparent sheet 17, the matter constituting the notes or memorandums. To erase the memorandum or note, it is only necessary for the operator to place his finger upon the manipulating handle 24 and depress the plate 19 against the action of the spring 22, and as the wax coating 21 disengages the soft pliable tissue sheet 18, the matter will become 20 obliterated and disappears, whereupon release of the manipulating handle 24 the spring will return the plate 19 to its former position for rendering the pad operative to receive the next memorandum. From the 25 description it will be noted that an operator may conveniently record memorandums or notes upon the pad by moving the stylus 26 thereover and to erase the memorandums he may depress the manipulating arm or handle 24 by the forefinger of the same hand, thus permitting use of the other hand for any purpose desired, such as for the holding of a telephone receiver in recording memorandums over the phone.

30 45 In Figures 5 and 6, the structure is identical to that shown in the preferred form with exception that instead of providing the manipulating handle 24, I provide a headed push button 24' which rises from the back plate 19 and extends through an opening 23' in the top wall 12 of the casing. The remaining part of the form shown in Figures 5 and 6 being identical to those shown in the preferred form, like reference characters refer 55 to like parts, and an added explanation is not believed necessary. In the operation to clear the pad in this particular form, it is only necessary for the operator to place his finger upon the head of the stud 24' and proceed to depress the same, thus causing the back plate 19 and its wax coating to move 60 out of engagement with the tissue sheet 18.

Having thus described the invention, what I claim as new and desire to secure by Letters Patent is:—

A memorandum pad comprising a rectangular shaped casing provided with an inclined top wall having a window opening therein, a glossy transparent sheet fitting against the inside of the top of said casing and closing the opening therein, a soft tissue sheet behind said glossy transparent sheet, a plate provided with a waxed coating on one side thereof, of a color contrasting with that of said tissue sheet, springs interposed between said plate and the bottom wall of said casing for urging said plate with its waxed coating against said tissue sheet, the top end of said casing having a slot therein and a manipulating member extending from said plate and outwardly through a slot in said casing.

In testimony whereof I affix my signature.
BENJAMIN SETTEL.
